UNITED STATES PATENT OFFICE.

ISIDORE MARKS, OF BOSTON, MASSACHUSETTS.

DESIGN FOR AN IMITATION PAPER PARASOL.

43,200.

Specification for Design.

Patented Oct. 29, 1912.

Application filed August 9, 1912. Serial No. 714,317. Term of patent 3½ years.

To all whom it may concern:

Be it known that I, ISIDORE MARKS, a subject of the Czar of Russia, residing at Boston, in the county of Suffolk and Commonwealth of Massachusetts, have invented a new, original, and ornamental Design for Imitation Paper Parasols, of which the following is a specification, reference being had to the accompanying drawing, forming a part thereof.

In the accompanying drawing the figure is a view, in elevation, of an imitation paper parasol, showing my new design.

I claim:

The ornamental design for an imitation paper-parasol, as shown.
